UNITED STATES PATENT OFFICE.

ALFRED VALLENTIN, OF CHICAGO, ILLINOIS.

SILO.

Application filed June 10, 1926. Serial No. 114,988.

The object of my invention is to combine the advantages of concrete and stave construction, to secure greater durability; to reduce loss from freezing and from temperature changes; and to provide a stave silo that shall always be substantially tight.

In the drawings Fig. 1 is a sectional elevation of a cylindrical silo, of my construction, in a plane laid through the axis of the 10 silo, with part of the structure broken away; Fig. 2 is a sectional top plan view of the walls of the silo, showing their construction at various levels; Fig. 3 is an enlarged detail of the sectional elevation shown in Fig. 15 1; Fig. 4 is an enlarged sectional elevation in the plane indicated by line 4—4 in Fig. 1; Fig. 5 is a detail elevation of a portion of the inner, wooden wall of my silo, viewed from the inside of the silo, with parts 20 broken away; Fig. 6 is a sectional plan view taken on line 6—6 in Fig. 5.

Referring to the drawings, on a concrete base ring 10, laid on a concrete foundation 11, there is erected a circular vertical concrete wall 12, provided with door openings 13. Wall 12 is preferably constructed of blocks 14 laid so as to overlap, and preferably tongued and grooved horizontally and vertically. At suitable intervals, about 30 three feet distant, vertically, adjoining layers of blocks 14 are provided with dovetail grooves 15, into which are entered wooden rings 16, made in sections, which 35 protrude from the inner face 17 of concrete wall 12 a distance of several inches. In door openings 13 there are inserted suitable wooden doorframes 18 which project beyond face 17 a sufficient distance to have their inner faces flush with the inner faces 40 of tongued and grooved wooden staves 19 which are set up against rings 16, about 2" distant from face 17, in a number of series, separated at suitable intervals by compression springs 20, interposed between the 45 several series of staves. Staves 19 are held in place against rings 16 not only by reason of the fact that their inner faces are narrower than their outer faces; the further fact that they are tongued and grooved; and the 50 pressure of springs 20; but also by vertical boards 21, overlapping each pair of staves 19 adjoining springs 20, which boards 21 are drawn against the underlying pair of staves 19 by internally threaded sleeves 22, 55 engaging threaded bolts 23, anchored in wall 12; sleeves 22 being provided with

preferably square heads 24 adapted to be engaged by a suitable socket wrench, and with outwardly projecting circular flanges 25, adapted to engage inwardly projecting flanges 26 at the bottom of suitable sockets 27 which are integral with metal plates 28, inlaid into the faces of boards 21 so as to be flush therewith. Springs 20 may be of any desired construction. In the drawings 60 I have shown them as elliptical springs, entered into suitable seats 29 in the adjoining faces 30 of staves 29, and there further held by horizontal pins 31, entered into faces 30 and projecting through openings 70 32 in springs 20.

Staves 19 are preferably set on an elevated, peaked ridge 33, formed on base ring 10, concentric with wall 12. In order to prevent staves 19 from slipping off this ridge 75 33, I prefer to provide their lower ends with grooves 34, fitting on ridge 33. Between ridge 33 and wall 12 I form a sloping drain-gutter 34^a, with its highest points adjoining door opening 13, and thence pitching 80 downward to a grated opening 35, in wall 12, opposite door openings 13. To close the spaces between wall 12 and staves 19 at the top, and at the same time to hold the upper ends of staves 19 in fixed position with 85 reference to wall 12, I provide preferably metallic sectional caps 36, having concentric depending flanges 37 and 38, to receive between them the upper ends of staves 19, and depending flange 39 to enter groove 40, 90 formed in the upper face of capblocks 41 of wall 12. Openings 42 are provided in caps 36 to allow passage of air entering through opening 35 and circulating upward between wall 12 and staves 19, through the spaces between rings 16 and boards 21. Between 95 boards 21 and those staves 19, against which boards are drawn by sleeves 22, I prefer to interpose elastic asbestos insulation strips 43 to exclude more perfectly all leakage of air 100 and moisture. The several doorframes 18 are connected at their inner ends in any suitable way so as to make a surface flush with the inner face of adjoining staves 19. A suitable roof 44 and suitable doors 45 105 are provided, of any convenient construction.

It is manifest that the silo construction above described might be deviated from in numerous particulars without departing from the essentials of my invention. All 110 such deviations I intend to cover by my claims.

I claim—

1. In a silo, the combination of an outer wall, preferably made of stony material, horizontal rings attached to the outer wall, 5 on the inside thereof, and an inner wooden wall, held against said rings without being attached to said rings.
2. In a silo, the combination of vertical wooden staves, arranged in a number of 10 series, means for preventing the staves from yielding outwardly, compression springs entered between the several series of staves, boards to cover the spaces between the several series of staves, and means for drawing 15 the boards into tight engagement with the adjoining staves.
3. In a silo, the combination of an outer wall, made of stony material, an inner wooden wall, separated from the outer wall 20 so as to form air spaces between the walls, and a base supporting both walls, said base being provided with a peaked elevated ridge, supporting the wooden wall, and with a sloping drain groove between such ridge and 25 the outer wall, leading to a suitable outlet.
4. In a silo, the combination of an outer wall of stony material, an inner wooden

wall separated from the outer wall so as to form air spaces, and means for holding the inner wall to the outer wall, consisting 30 of threaded bolts entered in the outer wall; internally threaded flanged sleeves engaging the bolts; and plates with sockets engaged by the sleeves, substantially as described.

5. In a silo, the combination of an outer 35 wall of stony material, an inner wooden wall separated from the outer wall so as to form air spaces, and means for closing the air spaces at the top, consisting of metal plates having concentric depending flanges, engaging both the upper ends of the staves and also a groove formed in the upper face of the stony wall.

6. In a silo, the combination of an outer 40 wall, preferably made of concrete blocks, made so as to form on the inside thereof, at suitable distances, horizontal dovetail grooves; wooden rings held in these grooves and projecting therefrom; an inner wooden wall; and means for holding the inner wall 45 in contact with the rings, except at suitable intervals.

ALFRED VALLENTIN.
